his Atty.

UNITED STATES PATENT OFFICE

2,076,957

BOAT STRUCTURE

Lawrence R. Lueck, El Monte, Calif.

Application March 28, 1935, Serial No. 13,379

1 Claim. (Cl. 114—65)

This invention relates to particularly constructed and shaped hulls for boats.

One of the objects of this invention is to design a boat hull that can be made from sheets produced in flat form to cover the whole side of the hull.

Another object is to create a hull with distinctly straight lines transversely to the curved lines that extend from bow to stern.

10 Another object is to simplify the construction of a boat.

Another object is to simplify the structure of a boat.

15 Another object is to eliminate or reduce seams in a boat.

Another object is to create more abruptly increasing surface and body for the different tilting positions of a boat.

20 Other objects will appear from the following description and appended claim as well as from the accompanying drawing, in which—

Fig. 1 is a fragmentary somewhat diagrammatical illustration of the manner in which the boat sides are marked and cut according to this 25 invention.

Fig. 2 is a fragmentary section through the keel and rudder structures on line 2—2 of Fig. 1.

Fig. 3 is a side elevation of a sailboat, partly broken away to show inside construction around 30 the rudder shaft in accordance with this invention.

Fig. 4 is a side elevation of a boat with a straight top, illustrating in dotted lines the necessity of trimming the upper edge of the sheets provided 35 according to this invention.

Fig. 5 is a fragmentary typical vertical cross section through a boat according to this invention.

Boats, large steam ships as well as the smallest 40 sport boats, are generally formed along distinct curves, from bow to stern at the different or various elevations, or levels, or horizontal planes, as well as when considered at cross sections of vertical planes at the different points between the 45 bow and stern.

Such curves can normally be produced only by making the sides of a boat in sections, or, particularly with boats made of wood, by narrow plankings, individually shaped to form the double 50 curves of the horizontal planes as well as of the vertical planes.

While the curves along the edges of horizontal planes are naturally desired and practically required, to follow so-called stream-lines from the 55

bow to the stern; the present invention involves distinct straight lines formed along the edges of vertical planes, or as seen along the up and down edges of vertical cross sections of a boat.

This arrangement allows the whole sides of a boat to be made in flat sheets, to be merely drawn into the desired shape around the hull of a boat from bow to stern; both sides of the boat being absolutely of the same size and shape while in flat form, and neither side requiring any special treatment or shaping before being drawn over the sides of the boat.

Fig. 1 illustrates a typical method of marking and cutting the lower edge of a sheet for the side of a boat, showing the simple manner in which such boat side is produced from a flat sheet without any bulging within any portion of such a sheet.

Whether such a side of a boat is made of a single sheet depends entirely on the size of the boat 20 and the size in which sheets of certain thickness can be had from the mill, and it should, therefore, be understood that when hereafter reference is made to a sheet for a boat side it should mean and include any sheet naturally and normally coming in a single sheet form from the mill 25 as well as individual pieces united into a sheet by welding or otherwise.

Such a uniting of individual pieces, however, is to be understood to be produced in flat form, 30 or at least without any bulging preparatory to being drawn over the side of a boat.

When such a boat-side has been produced in flat form, on being drawn over the side of a boat, the upper edge of the sheet naturally has a tendency to curve upwardly at the opposite ends above the deck of a boat in a manner indicated in dotted lines at 11 in Fig. 4, and as a result the upper edge must also be trimmed, to conform with the desired outlines of the finished boat. The amount 40 of trimming depends on individual requirements, since boats are designed with absolutely straight or level decks, such as indicated at 12 in Fig. 4 as well as also with curved decks, such as indicated at 13 in Fig. 3 and for a straight-deck boat, the upper edge of a sheet for the side of the hull naturally requires more of a trimming than with a curved deck.

Applicant, therefore, does not mean to limit 50 himself to any particular shaping of the upper edge of any sheet for any size or type of boat.

The lower edge, however, is illustrated in Fig. 1 as designed in a very specific manner.

A vertical construction line O—O is marked 55

off at a predetermined distance X from one end of the flat sheet, indicated in dotted lines at 14.

From the upper end of the line O—O the rear-curve 15 is drawn at the radius R_1' . At the same time certain points are marked off along the line O—O from its upper end downwardly, as indicated at a, b, c, d, e, f, g , and h , and a similar number of points are marked off along the lower edge of the sheet 14, as indicated at $a_1, b_1, c_1, d_1, e_1, f_1, g_1$, and h_1 . Vertical construction lines 16 are drawn upwardly from the points at the lower edge of the sheet, and these lines 16 are connected by sections of circles by the different radius-lines or curves produced by such means as indicated at $R_2, R_3, R_4, R_5, R_6, R_7, R_8, R_9$, to result in the front-curve 17.

This completes one side of a boat as far as the lower curve is concerned. A second sheet is produced in a similar manner.

20 A keel structure for this boat hull is procured in a similar manner, a radius R_{10} being indicated to result in a keel-edge 18.

The keel structure is also made in two equal sheets, the keel-edges of the two being united, as 25 by welding, the upper edges of the two sheets being trimmed, depending entirely on the spacing desired between the upper edges of the keel structure, and this upper edging of the keel structure is also trimmed to suit the trimming of 30 the boat sides, to which the keel is united as indicated at 19 in Fig. 5.

From the cross section of Fig. 5 it should be clear that the finished and attached keel structure is spaced differently than the two sides of the 35 boat proper. The keel-structure K merely serves to hold weight material such as lead, while the upper boat structure B must be designed for inside comfort as well as to result in a desired action of the completed boat, the two structures K 40 and B being therefore not necessarily of a uniform shape on the outside.

Nevertheless, individually, both structures K and B show distinct straight lines in the cross sections taken at any point between the bow and stern similar to the showing of the typical cross section of Fig. 5, in which the keel structure has the straight lines between the lower keel edge 18 and the joints at 19, and the boat proper has

the straight lines between the joints 19 and the upper deck-edge 20.

The keel sides are reinforced by the tie-rods 21. An apertured partition 22, at about the joint between the keel K and the boat proper B also serves 5 to reinforce the keel as well as the lower end of the main sides, the apertures in this partition serving to allow a removal or adding of weight material.

Stronger reinforcements are provided between 10 the opposite sides of the boat proper B, stringers 23 at the same time serving to support a floor 24, and the wide plates 25, provided throughout the full length of the boat, serve at the same time as floor or support for the bunks inside of the 15 boat. These plates 25 are furthermore reinforced by upright plates 26.

A full cross partition is preferably provided at about the point where a mast is to be supported as indicated at 27 in Fig. 5. At other points, 20 gusset-plates 28 are provided to reinforce and brace the cabin and the hull.

Though there is a rather distinct offset or bend in the vertical lines at the joints 19, in the longitudinal lines all offsets or variation of lines 25 are carefully avoided, as, for instance, between the rudder indicated at 29 and the boat or keel, the outer contours of the rudder clearly being a continuation of the lines of the adjoining structure, as indicated by the lines 30 and 31 in Fig. 30 2, while the illustration in Fig. 3 just as clearly shows that the rudder 29 is practically a part of the keel structure K.

Having thus described my invention, I claim:—

In a boat construction, a distinct boat portion, 35 and a distinct keel portion, both being hollow and united at a certain divisional level and lines, bow and stern edges being curved between the keel and deck, the boat portion having distinctly straight lines in the upward direction between the divisional level and the deck, the keel portion having distinctly straight lines between the lower-most keel edge and the divisional level in an upward direction, and the deck edges being spaced so much more than the edges at the divisional level as to form a distinct sharp bend in the combined lines at any point between the bow and stern. 40 45

LAWRENCE R. LUECK.
